[57] CLAIM

The ornamental design for a combined door and window decoration, as shown and described.

DESCRIPTION

FIG. 1 is an environmental front view of a first embodiment of a combined door and window decoration showing my new design;

FIG. 2 is a right side elevational view with the left side being a mirror image thereof; and,

FIG. 3 is a front elevational view of a second embodiment thereof.

The right and left views of the second embodiment are substantially the same as the first embodiment, and the rear of the combined door and window decoration is plain and unornamented. The broken lines shown in FIG. 1 are for illustrative purposes only and form no part of the claimed design.
